PORTABLE MOTOR FOR CONCRETE VIBRATORS

Ona Louis Whitman, Glendale, Calif., assignor to Viber
Company, Burbank, Calif., a corporation of California

Filed Aug. 1, 1966, Ser. No. 3,301

Term of patent 14 years

(Cl. D54—14)

FIG. 3.

FIG. 4.

FIG. 1 is a perspective view of a portable motor for concrete vibrators showing my new design;

FIG. 2 is an end view of the same;

FIG. 3 is a side elevational view of the same; and

FIG. 4 is a front view of the same.

The dominant features of my design reside in the portions shown in full lines.

I claim:

The ornamental design for a portable motor for concrete vibrators, as shown and described.
